UNITED STATES PATENT OFFICE.

DANIEL HARRINGTON, OF NEWARK, NEW JERSEY.

SWITCH TIE-PLATE.

1,152,314.

Specification of Letters Patent. Patented Aug. 31, 1915.

Application filed January 26, 1915. Serial No. 4,461.

To all whom it may concern:

Be it known that I, DANIEL HARRINGTON, a citizen of the United States, and a resident of Newark, in the county of Essex and State 5 of New Jersey, have invented a new and Improved Switch Tie-Plate, of which the following is a full, clear, and exact description.

The object of the invention is to provide a new and improved switch tie plate, arranged to prevent the main rail from spreading by providing a firm support for the inner edge of the rail base and without obstructing the free movement of the switch rail.

15 In order to accomplish the desired result, use is made of a tie plate having in its top a recess extending across the width of the plate for the base of the rail to rest on, the inner side wall of the recess being undercut 20 for the reception of the inner edge of the rail base, a brace abutting against the outer face of the web of the rail and having a base plate fitting into the outer portion of the said recess adjacent the rail, the inner edge 25 of the said base plate abutting against the outer edge of the rail base, and the outer edge of the said base plate abutting against the outer side wall of the said recess. Use is also made of registering spike holes in the 30 tie plate and base plate for the reception of a spike and registering notches are formed at the inner corners of the rail base and the tie plate for the passage of spikes, the heads of which engage the top of the rail base and 35 the shanks of which abut against the outer edge of the rail base.

A practical embodiment of the invention is represented in the accompanying drawings forming a part of this specification, in 40 which similar characters of reference indicate corresponding parts in both views.

Figure 1 is an elevation of the switch tie plate as applied and showing the main rail in cross section on the line 1—1 of Fig. 2; 45 and Fig. 2 is a plan view of the same with one of the rail spikes shown in section.

On top of the railroad tie A is placed a switch tie plate B, provided on its upper face with a recess C extending in the direction of the length of the rail D, from one edge of the tie plate B to the other edge thereof, so as to form a support for the base D' of the rail D to rest on. The inner side wall C' of the recess C is provided with 50 an undercut for the reception of the inner edge of the rail base D', to hold the rail base 55

down in position on the bottom of the recess C and thus prevent outward tilting or spreading of the rail. When the tie plate B is extended inwardly a distance beyond the 60 wall C' it forms a support for the switch rail E to slide on, it being understood that by the arrangement described the switch rail E can be readily moved toward and from the rail D as no obstruction whatever is in 65 the way of the switch rail E and at the same time the inner edge of the rail base D' is properly supported by the undercut wall C'. The outer face of the web D² of the rail is 70 engaged by a brace F provided with an integral base plate F' fitting into the outer portion of the recess C. The inner edge of the base plate F' abuts against the outer edge of the rail base D', and the outer edge of the base plate F' abuts against the outer 75 side wall C² of the recess C. By the arrangement described the rail D is properly braced and is thus held against outward movement especially as the edges of the rail base D' are engaged by the undercut wall C' 80 and the inner edge of the base plate F'.

The base plate F' is provided adjacent the outer end of the brace F with a spike hole F² in register with a spike hole B' formed in the tie plate B, and a spike G is 85 driven through the said registering holes F² and B' and into the tie A to fasten the base plate F' in position on the tie plate B and to fasten the latter in position on the tie A. It is understood that the head G' of 90 the spike G rests on top of the base plate F' to hold the latter down. The base plate F' is provided at the inner corners with notches F³ in register with notches B² formed in the tie plate B so that the rail spikes H can be 95 driven through the said registering notches F³ and B² and into the tie A. The base H' of the rail spikes H rests on top of the outer portion of the rail base D', and the shanks of the said spikes H abut against the 100 outer edge of the rail base D' to assist in holding the rail D against outward shifting. By reference to Fig. 2, it will be noticed that the spikes H are located directly opposite the ends of the undercut side wall C' 105 of the tie plate B to insure a firm holding of the rail in place in the recess C of the tie plate B.

The inner end of the tie plate B is preferably provided with spike holes B³ to receive spikes I driven into the tie A for holding the inner end of the tie plate down on 110

the tie A. It is understood that the heads of the spikes I are out of the range of movement of the switch rail E.

A switch tie plate B, as shown and described is placed on each tie A crossed by the switch rail E so that the main rail D is properly supported along its inner edge, and the switch rail E is free to move toward and from the main rail on closing or opening the switch.

The switch tie plate shown and described is composed of but two parts, which can be readily assembled after the main rail D is placed in position in the recess C, and on spiking the switch tie plate to the tie A by the use of the spikes G and H the parts are fastened together.

Having thus described my invention, I claim as new and desire to secure by Letters Patent:

1. In a switch tie plate, a tie plate having in its upper face a recess for the base of the main rail to rest on, the inner side wall of the recess having an undercut into which fits the inner edge of the rail base, a brace adapted to abut against the outer face of the web of the main rail, the said brace having a base plate fitting into the outer portion of the said recess, the inner edge of the said base plate abutting against the outer edge of the rail base, and the outer edge of the said base plate fitting the outer side wall of the said recess, the said tie plate being extended a distance beyond the inner side wall of the said recess to form a support for the switch rail to slide on, the said base plate and the said tie plate having registering apertures, a spike passing through the said apertures when driven into the railroad tie, the head of the spike resting on top of the base plate, the latter having notches at the inner corners and the said tie plate having notches in register with the said base plate notches, and spikes engaging the said notches.

the base plate, the latter having notches at the inner corners and the said tie plate having notches in register with the said base plate notches, and spikes engaging the said notches.

2. In a switch tie plate, a tie plate having in its upper face a recess for the base of the main rail to rest on, the inner side wall of the recess having an undercut into which fits the inner edge of the rail base, a brace adapted to abut against the outer face of the web of the main rail, the said brace having a base plate fitting into the outer portion of the said recess, the inner edge of the said base plate abutting against the outer edge of the rail base and the outer edge of the said base plate fitting the outer side wall of the said recess, the said tie plate being extended a distance beyond the inner side wall of the said recess to form a support for the switch rail to slide on, the said base plate and the said tie plate having registering apertures, a spike passing through the said apertures when driven into the railroad tie, the head of the spike resting on top of the base plate, the latter having notches at the inner corners and the said tie plate having notches in register with the said base plate notches, and spikes engaging the said notches, the shanks of the said spikes abutting against the outer edge of the rail base and the heads of the said spikes resting on top of the rail base.

In testimony whereof I have signed my name to this specification in the presence of two subscribing witnesses.

DANIEL HARRINGTON.
